UNITED STATES PATENT OFFICE.

FRANK H. HARTUNG, OF NORWOOD, OHIO, ASSIGNOR, BY DIRECT AND MESNE ASSIGNMENTS, TO THE U-NEED-A STARTER COMPANY, OF CINCINNATI, OHIO, A CORPORATION OF OHIO.

AUTOMOBILE-ENGINE STARTER.

1,220,511.

Specification of Letters Patent.

Patented Mar. 27, 1917.

Application filed October 20, 1916. Serial No. 126,659.

To all whom it may concern:

Be it known that I, FRANK H. HARTUNG, a citizen of the United States, and a resident of Norwood, in the county of Hamilton and State of Ohio, have invented certain new and useful Improvements in Automobile-Engine Starters, of which the following is a specification.

My invention relates to starting devices 10 and its object is to enable the driver of an automobile to start the engine without leaving the seat and without danger of injury either to the operator, or to the starter or engine if "back-fire" occurs.

15 In the drawing:

Figure 1 is a front elevation of the front end of the frame of an automobile with my invention installed thereon, part of the handle rod being broken away for lack of 20 space;

Fig. 2 is a plan view of the main part of the starter and part of the crank shaft on which it is mounted;

25 Fig. 3 is a longitudinal section on a line corresponding to the line 3—3 of Fig. 1;

Fig. 4 is a detail plan view of part of the lever and its hub with the releaser mounted thereon;

30 Fig. 5 is a cross-section on a plane corresponding to the line 5—5 of Fig. 2; and

Figs. 6, 7 and 8 are diagrammatical sectional views representing the various relative positions of the parts during different stages of the operation, the section in each 35 instance being on a plane corresponding to the line 6—6 of Fig. 2.

As I prefer to construct my invention, the crank shaft 1 of the engine to be started has fitted on its end a sleeve 2, which has 40 projecting past the end of the shaft, a suitable toothed clutch member 3 for the application of the ordinary well known starting crank, if it be desirable or necessary to start the engine in this way. The sleeve 2 extends back along the shaft 1 and around 45 its rear end part is fitted the collar 4, which with this sleeve 2 is fixed to turn with the shaft 1 by means of a pin 5, passing diametrically through it and the sleeve of the shaft. 50 This collar 4 has a forwardly projecting annular peripheral flange 6, so that there is an annular space around between this flange and the sleeve 2, immediately forward of the collar 4. Fitting around the 55 sleeve 2 between the collar 4 and the for-

ward part 3 above alluded to, the arm 7 has the hub 8; and fitting around this hub 8 between the collar 4 and a forward annular flange 9 on the hub 8 is the releaser 10, which preferably has an annular flange 60 11 fitting back against the front edge of the flange 6 of the collar 4.

The hub 8 has in its convex surface a series of depressions 12 (Figs. 6 to 8, inclusive) which, as here shown, are three 65 in number; and the releaser 10 has a corresponding number of slots 13 adapted to register with the depressions 12, so that spaces are formed in which are held cylindrical gripping members 14 with their axes 70 parallel with the axes of the shaft 1 and held back in the spaces by the inner side of the forward flange 11 of the releaser, which forms the front end of the respective slot 12. 75

As shown in the drawing and as usually constructed, the engine is to be turned clock-wise, looking at it from the front. The side of each depression 12 that is advanced in the above direction is comparatively short 80 and almost radial of the hub 8, while the other side is longer and far less inclined to the normal convex surface of the hub. Thus, if the hub is turned clock-wise, the gripping members 14 ride up on the less 85 inclined side of the depression 12 and are wedged on the inner concave surface of the flange 6 of the collar 4, causing the collar 4 and consequently the shaft 1, and incidentally the sleeve 2, to turn in the same 90 direction. The arm 7 extends from the hub 8 over to the left. Thus by pulling up on the arm 7 the engine shaft 1 is rotated through part of a revolution, depending upon how far around the arm 7 is pulled. 95 But when the pulling on the arm ceases, the engine shaft 1 may continue to turn and will then merely tend to force the gripping members 14 down into the depressions 12, 100 away from the inner side of the flange 6, destroying the frictional connection with the arm 7.

The construction so far described is sufficient for starting the engine, and safe, so long as the engine does not run in the wrong direction, as when "back-fire" occurs. In fact this is true of almost any ordinary starting crank that may be applied to the part 3.

With my invention, if the engine, during 110

the process of starting, is caused to rotate in the wrong direction, or as here shown, counter clock-wise, the releaser 10 acts to terminate the frictional connection above described. Thus the releaser 10 has a radially projecting finger 15 at the left side, which, as the releaser turns counter clock-wise, engages with a stationary member 16 at the left side of the device close to the flange 11 of the releaser and prevents further turning of the releaser in this direction. The slots 13 in the releaser, the sides of which flank the cylindrically engaging members 14, are inclined from coincident radii radially outward in the direction of proper turning of the parts, with the result that when the releaser 10 is prevented from further turning in the improper direction, the slightest additional improper turning of the other parts, *i. e.*, the shaft 1, sleeve 2 and collar 4, brings the engaging members 14 against the side of the respective slot 13 that tends to wedge the engaging member 14 radially inward away from the inside of the flange 6. Thus the driving connection between the arm 7 and the shaft 1 is destroyed immediately at the beginning of any reverse rotation of the engine before any damage can occur to either the operator or mechanism.

The releaser 10 has, radially inward on its front end, to come adjacent to the outward surface of the hub 8 next to its flange 9, an annular recess in which is located a small helical spring 17 compressed between a lug or pin 18 on the releaser and a lug or pin 19 on the hub. This spring causes the releaser to resume its normal position after it has acted in the above manner. The member 16 for the finger 15 to engage with, is present, in many automobiles to which my invention is applicable, in the form of the upper edge part of a frame casting of substantially semi-circular cross-section, under the forward part of the engine shaft as seen in Fig. 1. Also, in a great many automobiles, the part of the shaft to which my invention is applied is regularly provided with a pulley for driving the ventilating fan. I make the peripheral surface of the collar 4 and its flange 6 to correspond in size and shape with such a pulley, and by allowing the fan belt to pass therearound it serves to drive the fan the same as would the regular pulley.

The upper part of the arm 7, a short distance from the hub 8, has a lug 7' which receives the hook 20 which in turn has connected to it one end of a tension spring 21. Fastened over the top of the frame of the automobile at the left side is a rod 22 that extends down and has connected to its lower end the other end of the tension spring 21. Thus the spring 21 normally holds the arm 7 down in an almost horizontal position at

the left, but readily yields to allow the arm 7 to be pulled upward and over to the right.

Flanking and pivoted to the free end part of the arm 7 are links 23 that extend up and receive between them a roller 24 which has a peripheral groove 25. Rigidly mounted on the part of the frame at the right is a bracket 26 which has a fork extending laterally inward but somewhat inclined forwardly, and a roller 27 is journaled between the members 28 of the fork on a suitable pin passing downward therethrough. A chain 29 has one end secured to a lug 30 on the upper end part of the bracket 26, passes to the left and down over the roller 24 and down to the right under said roller and forwardly around the roller 27, and then rearwardly and upwardly, where it has its other end connected to the lower forward end of a handle rod 31 which may extend to within a convenient distance of the seat of the automobile, where it may be provided with a suitable handle 32. Preferably, the roller 27 has its peripheral surface of a slightly concave cross-section, so that the chain 30, passing therearound, is kept from riding up against the upper member 28 of the fork of the bracket 26. The groove 25 in the roller 24 admits the alternate links of the chain 29, which lie perpendicular to the periphery 95 of the roller in passing therearound.

With the construction just described, it is only necessary to pull backwardly and upwardly on the handle 32, whereupon the stretches of the chain 29 are reduced in length with the result of pulling the arm 7 up and over to the right to the extent of nearly one-half revolution; which is sufficient to secure an explosion in the engine. If the engine does not start with this effort, the entire mechanism is allowed to be pulled back to its initial position by the spring 21, whereupon the operation may be repeated. The loop of the chain 29, having two stretches to be shortened in the operation results in a mechanical advantage that greatly relieves the operator in the starting operation. As will be readily understood, the spring 21 is strong enough only to readily pull the parts back to their initial positions, during which there is no resistance to be overcome other than a small proportion of the weights of the parts and the friction of the bearings.

From the foregoing it will be seen that not only is a device provided by means of which the engine may be started without necessitating the driver of the automobile leaving the seat thereof, but the starting is accomplished with much less exertion on the part of the operator and, with the releaser, there is a far greater degree of safety as compared with starting with the ordinary crank, such as is used on the part 3.

I prefer to provide the part 3, as before

alluded to, since it occupies very little space, is very inexpensive and may be very convenient in case of accident to the mechanism of my invention. In fact, on many automobiles to which my invention is applicable, this part 3 and the sleeve 2 are present and require only the substitution of the other members of my improved mechanism for the fan driving pulley as hereinbefore described. It will be understood, however, that the sleeve 2 and part 3 are not essential to my invention and also that other minor modifications may be made without departing from the scope and spirit of the following claims:

1. In combination, a rotatable engine element, a hub element and a releaser journaled concentric with said engine element, one of said elements having a depression opening 20 toward the other element with a bottom inclined circumferentially of said elements, said releaser having a slot to register with said depression, a gripping member in said depression and slot, to be wedged between 25 said inclined bottom of said depression of said element and the adjacent part of the other of said elements when said hub element is rotated in engine-starting direction, one side of said slot being inclined circumferentially of said releaser to wedge said gripping member away from its wedged position between said bottom of said slot and said other member when said engine element is rotated in the opposite direction relative to said releaser, means to stop said releaser from rotating in said opposite direction, yieldable means to return said releaser from its stopped position, and means connected to said hub element to rotate it in engine-starting direction.

2. In combination with an engine and its crank shaft, a collar fixed on said crank shaft coaxial therewith, a hub and a releaser journaled concentric with said shaft and collar, said hub having a depression in its peripheral surface, said releaser having a part with a slot to register with said depression, and said collar having a part extending across said depression and slot, a gripping member in said depression and slot, the bottom of said depression being inclined circumferentially of said hub to wedge said gripping member out against said part of said collar when said hub is rotated in engine-starting direction, and one side of said slot being inclined circumferentially of said releaser to wedge said gripping member away from said part of said collar when said collar is rotated in the opposite direction relative to said releaser, means to stop said releaser from rotating in said opposite direction, yieldable means to return said releaser from its stopped position, and means connected to said hub to rotate it in engine-starting direction.

3. In combination with an engine and its crank shaft, a collar fixed on said crank shaft coaxial therewith, a hub and a releaser journaled concentric with said shaft and collar, said hub having a depression in its peripheral surface, said releaser having a part with a slot to register with said depression, and said collar having a part extending across said depression and slot, a gripping member in said depression and slot, the bottom of said depression being inclined circumferentially of said hub to wedge said gripping member out against said part of said collar when said hub is rotated in engine-starting direction, and one side of said slot being inclined circumferentially of said releaser to wedge said gripping member away from said part of said collar when said collar is rotated in the opposite direction relative to said releaser, means to stop said releaser from rotating in said opposite direction, yieldable means to return said releaser from its stopped position, and yieldable means to rotate said hub in said opposite direction.

4. In combination with an engine and its crank shaft, a collar fixed on said crank shaft coaxial therewith, a hub and a releaser journaled concentric with said shaft and collar, said hub having a depression in its peripheral surface, said releaser having a part with a slot to register with said depression, and said collar having a part extending across said depression and slot, a gripping member in said depression and slot, the bottom of said depression being inclined circumferentially of said hub to wedge said gripping member out against said part of said collar when said hub is rotated in engine-starting direction, and one side of said slot being inclined circumferentially of said releaser to wedge said gripping member away from said part of said collar when said collar is rotated in the opposite direction relative to said releaser, means to stop said releaser from rotating in said opposite direction, said releaser and said hub having parts opposed on an arc concentric with said shaft, a spring compressed between these parts to return said releaser from its stopped position, and means connected to said hub to rotate it in engine-starting direction.

5. In combination with an engine and its crank shaft, a collar fixed on said crank shaft coaxial therewith, a hub and a releaser journaled concentric with said shaft and collar, said hub having a depression in its peripheral surface, said releaser having a part with a slot to register with said depression, and said collar having a part extending across said depression and slot, a gripping member in said depression and slot, the bottom of said depression being inclined circumferentially of said hub to wedge said gripping member out against said part of

5 said collar when said hub is rotated in engine-starting direction, and one side of said slot being inclined circumferentially of said releaser to wedge said gripping member away from said part of said collar when said collar is rotated in the opposite direction relative to said releaser, means to stop said releaser from rotating in said opposite direction said releaser and said hub having parts opposed on an arc concentric with said shaft, a spring compressed between these parts to return said releaser from its stopped position, and yieldable means to rotate said hub in said opposite direction.

10 6. In combination with an engine and its crank shaft, a collar fixed on said crank shaft coaxial therewith, a hub and a releaser journaled concentric with said shaft and collar, said hub having a depression in its peripheral surface, said releaser having a part with a slot to register with said depression, and said collar having a part extending across said depression and slot, a gripping member in said depression and slot, the bottom of said depression being inclined circumferentially of said hub to wedge said gripping member out against said part of said collar when said hub is rotated in engine-starting direction, and one side of said slot being inclined circumferentially of said releaser to wedge said gripping member away from said part of said collar when said collar is rotated in the opposite direction relative to said releaser, means to stop said releaser from rotating in said opposite direction, yieldable means to return said releaser from its stopped position, an arm fixed to said hub, a flexible connection having a loop with one end part fixed, said loop being movably connected to said hub, radially outward from said hub, to rotate said hub in engine-starting direction by pulling

15

the other end part of said loop, and yieldable means to rotate said hub in said opposite direction.

7. In combination with an engine and its
crank shaft, a collar fixed on said crank
shaft coaxial therewith, a hub and a releaser
journaled concentric with said shaft and col- 50
lar, said hub having a depression in its per-
ipheral surface, said releaser having a slot
to register with said depression, and said 55
collar having a part extending across said
depression and slot, a gripping member in
said depression and slot, the bottom of said
depression being inclined circumferentially
of said hub to wedge said gripping member 60
out against said part of said collar when
said hub is rotated in engine-starting direc-
tion, and one side of said slot being inclined
circumferentially of said releaser to wedge
said gripping member away from said part 65
of said collar when said collar is rotated in
the opposite direction relative to said releaser,
means to stop said releaser from rotat-
ing in said opposite direction, yieldable
means to return said releaser from its stopped 70
position, an arm fixed to said hub, a roller
journaled on said arm radially outward
from said hub, a fixed bracket, a roller jour- 75
naled in said bracket, a flexible connection
with one end fixed to said bracket and pass-
ing around said roller on said arm and
around said roller in said bracket to rotate
said hub in engine-starting direction by pull-
ing said flexible connection where it extends
past said roller in said bracket, and yield-
able means to rotate said hub in said op- 80
posite direction.
